US0D1037671S

(12) United States Design Patent (10) Patent No.: US D1,037,671 S
(45) Date of Patent: * Aug. 6, 2024

(54) TOOTHBRUSH

- (71) Applicant: Colgate-Palmolive Company, New York, NY (US)
- (72) Inventors: Youran Wang, JiangSu (CN); Guoqiang Liu, Yangzhou (CN); Fan Gang Xie, Shanghai (CN); Yanmei Ji, Jiangsu (CN)
- (73) Assignee: Colgate-Palmolive Company, New York, NY (US)
- () Term: 15 Years
- (21) Appl. No.: 29/810,323
- (22) Filed: Oct. 4, 2021

Related U.S. Application Data

(57) CLAIM

The ornamental design for a toothbrush, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a toothbrush according to an embodiment of the new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.

The broken lines illustrating portions of the a toothbrush form no part of the claimed design. The dot-dash broken lines define the bounds of the claimed design and form no part thereof.

1 Claim, 4 Drawing Sheets
(4 of 4 Drawing Sheet(s) Filed in Color)
